Des. 196,617
Patented Oct. 15, 1963

196,617

COMBINED CAMERA AND FLASHGUN

Jay Doblin, Chicago, Ill., assignor to Whitehouse
Products, Inc., Brooklyn, N.Y., a corporation of New
York

Filed Apr. 9, 1963, Ser. No. 74,374

Term of patent 14 years

(Cl. D61—1)

FIG.2

FIG.1

FIG.3

FIG.4

FIG.5

FIG.6

FIG.7

FIG. 1 is a front elevational view of a combined camera and flashgun showing my new design;

FIG. 2 is a right-side elevational view thereof;

FIG. 3 is a rear elevational view thereof;

FIG. 4 is a top plan view thereof;

FIG. 5 is a bottom plan view thereof;

FIG. 6 is a top front isometric view thereof with the flashgun removed; and

FIG. 7 is a rear elevational view thereof.

I claim:

The ornamental design for a combined camera and flashgun, as shown.
